assignor to Lever Brothers & Unilever Limited,
Port Sunlight, England, a company of Great
Britain

Application December 31, 1942, Serial No. 470,894
In Great Britain December 31, 1941

6 Claims. (Cl. 257—256)

This invention relates to apparatus for cooling soap and similar solidifiable materials which are to be cooled into slabs or blocks, and relates particularly to improvements in cooling cells for use in cooling apparatus of the filter press type, wherein rectangular water-cooled metal cells are placed alternately in multiple arrangement with rectangular moulding frames, the liquid material to be cooled being fed to the latter through openings or ports in the cooling cells.

The cooling cell used in this type of apparatus consists normally of a fabricated chamber in which two rectangular polished metal plates, such as sheets of stainless steel or nickel-clad steel, form the cooling faces for the material contained within the moulding frames. As these plates are subjected to an appreciable external pressure by the material and a small but not negligible internal pressure by the cooling water, they are provided with internal stiffeners, normally attached by welding to both plates in such a way that a plurality of passages is formed for the circulation of the cooling water. The edges of the plates are generally welded to a skeleton frame to eliminate leaks due to the internal pressure.

It is found in practice that cells constructed as outlined above suffer from various drawbacks and defects, chief amongst which are (1) susceptibility of the welded places to corrosion, which affects the surface and frequently gives rise to leaks around the edges, (2) distortion of the surface of the plates by the heat of the welding process at numerous points, (3) slow rate of heat transmission on account of low velocity of the cooling water and (4) low space utilisation.

It is an object of the invention to provide a cooling cell in which the risk of leakage is eliminated or materially reduced and heat transfer and space utilisation are improved.

The invention consists in a cooling cell for cooling apparatus of the filter press type, which comprises in combination a narrow rectangular chamber, the side walls of which constitute the cooling surfaces, a stiffening grid comprising a plurality of substantially vertical bars and withdrawably disposed inside the chamber, the depth of the grid being such that the side walls rest on and are supported by the vertical bars, and a water inlet pipe horizontally arranged inside the chamber near the top thereof and provided with holes or slits for the uniform discharge of the cooling water onto the inner faces of the side walls.

One specific embodiment of a cooling cell ac-

cording to the invention designed for use in soap-cooling apparatus will now be described by way of example and with reference to the accompanying drawings, in which

- 5 Figure 1 is an isometric view of the rectangular chamber with a portion of one of the surface plates broken away.
- 10 Figure 2 is an isometric view of the stiffening grid.
- 15 Figure 3 is an elevation of the assembled cooling cell with the front surface plate removed, and
- 20 Figure 4 illustrates the position of the water inlet pipe in the chamber.
- 25 The rectangular chamber is constructed of a frame comprising the three members 1, 2 and 3 drilled and tapped for the attachment of the surface plates 4 and 5. The fourth member 6 of the frame carries the stiffening grid formed
- 30 of bars 7 and is provided with lugs 8 and 9 for attachment to the side members 2 and 3. The two surface plates 4 and 5 consisting of relatively thin sheets of stainless steel or nickel-clad steel are secured to the assembled frame by countersunk screws 10 with the aid of a plastic jointing compound. The depth of the grid is such that the inner faces of the surface plates 4 and 5 rest on the grid, the bars 7 being pitched at such intervals as to provide, without need for attachment, effective support for the surface plates.
- 35 A transverse rod 11, which may be secured to the bars 7 by welding, serves to keep the bars in position.
- 40 The water inlet pipe 12 extending through holes 13 and 14 in the side members 2 and 3 and holes 15 in the bars 7 is provided along its whole length with two rows of small holes 16 and 17 so positioned as to direct the cooling water onto the inner faces of the surface plates to form a continuous fast moving descending film thereon.
- 45 The water inlet pipe may be of round, elliptical or any other suitable cross section, and in place of the small holes shown in the drawings narrow longitudinal slits may be provided. An outlet opening 18 for the cooling water is arranged in one side of the frame, the cooling water flowing to the outlet opening through the small space left between the lower end of the grid and the bottom member 1 of the frame.
- 50 A passage 19 is provided for the flow of the liquid soap through the cooling cell between adjacent soap-moulding frames, and such passage is preferably formed by a composite and readily uncoupled ring joint so as to permit either sur-
- 55 face plate to be removed if desired.

In order to facilitate the lifting out of the grid from the chamber, an eye member 20 is provided in the centre of the top member 6 of the frame. The projecting screws 21 and 22 together with the threaded elements 23 and 24 serve for the attachment of the straps by which the cooling cell is suspended in the cooling apparatus.

It will be observed that the novel cooling cell according to the invention possesses amongst others the following advantages over the normal construction of cooling cell now in use:

The stiffening structure is not welded to the surface plates, so that the original truth of the plates is not disturbed and the risk of corrosion greatly reduced. The possibility of water leakage is practically eliminated, as no internal pressure exists. With the internal grid providing adequate support for the plates without need for attachment, the plates can be formed from relatively thin sheets having a low resistance to heat transfer. Moreover, heat transfer is further improved by the high velocity of the cooling water film which increases as the temperature of the water rises. The novel cell has a materially lower heat capacity than those which are operated full of water. The cell may be made narrower than the known constructions, as the minimum thickness is only limited by the width of the water inlet pipe. The cell therefore occupies less space and thus increases the capacity of the cooling apparatus. Finally the interior is made completely accessible for inspection and cleaning by the removal of either of the surface plates or the withdrawal of the stiffening grid.

I claim:

1. A cooling cell comprising two side frame members connected by a bottom frame member, and two substantially rectangular side plates secured to said frame members to form a narrow rectangular chamber open at the top, in combination with a removable stiffening grid insert for said chamber comprising a top frame member having a plurality of substantially vertical bars depending therefrom and a transverse bar near the lower portion of said vertical bars for holding said vertical bars in position, the edges of said bars vertically slidably engaging the inner surfaces of said side plates when said stiffening grid is inserted into said chamber, and the ends of said top frame member being securable to the tops of said side frame members and the upper margins of said side plates being securable to the sides of said top frame member after said grid is inserted to close the top of said chamber and complete the cooling cell.

2. A cooling cell comprising two side frame members connected by a bottom frame member, and two rectangular side plates secured to said members to form a narrow rectangular chamber open at the top, means forming a passage from the outside of one plate through said chamber to the outside of the other plate and spaced from said side and bottom frame members, in combination with a stiffening grid comprising a top frame member having a plurality of substantially vertical bars depending therefrom and held in position by a transverse bar near the lower portion of said vertical bars, said bars being constructed and arranged to clear said passage-forming means when said stiffening grid is inserted into said chamber with the edges of said bars vertically slidably engaging the inner surfaces of said side plates.

3. A cooling cell for cooling apparatus of the filter press type, comprising a narrow rectangular

chamber having side walls which constitute the cooling surfaces, and a plurality of substantially vertical bars transversely disposed in spaced relation inside said chamber for supporting said side walls against outside pressure, each of said bars having an aperture near the top thereof, in combination with a cooling fluid inlet pipe passing horizontally through said apertures and provided with openings for the uniform discharge of the cooling fluid outwardly and downwardly through the spaces between adjacent pairs of said bars onto the inner faces of said side walls supported thereby.

4. A cooling cell for cooling apparatus of the filter press type, comprising in combination a narrow rectangular chamber, the side walls of which constitute the cooling surfaces, a stiffening grid comprising a plurality of substantially vertical bars and withdrawably disposed inside said chamber, the depth of said grid being such that said side walls rest upon and are supported by said vertical bars, and a cooling fluid inlet pipe horizontally disposed inside said chamber near the top thereof and passing through apertures in the bars of said grid and provided with openings for the uniform discharge of the cooling medium outwardly and downwardly between said bars and onto the inner faces of said side walls to form a continuous fast moving descending film thereon, and an outlet adapted to discharge said medium at a rate sufficient to prevent accumulation of said cooling medium which would fill said cell.

5. A cooling cell for cooling apparatus of the filter press type, comprising a rectangular frame having a top member detachably secured to the vertical side members of said frame and carrying a stiffening grid formed by a plurality of substantially vertical bars held in position by a transverse bar, two rectangular side plates attached to said frame, and a water inlet pipe disposed substantially horizontally inside said chamber near the top thereof and passing through holes in said side members and said vertical bars, said water inlet being provided substantially along its whole length with two rows of small openings positioned so as to direct the cooling water supplied to said pipe on to the inner faces of said two rectangular side plates to form a continuous fast moving descending film thereon to effect rapid heat transfer with low heat capacity.

6. A cooling cell for cooling apparatus of the filter press type, comprising a narrow rectangular frame, a pair of heat conducting plates attached to opposite sides of said frame and thereby spaced apart to comprise a narrow rectangular chamber, said plates forming the side walls of said chamber and constituting the cooling surfaces of said cell, said frame having a top member detachably secured to the vertical side members of said frame and carrying a stiffening grid formed by a plurality of substantially vertical bars held in position by a transverse bar passing through apertures in the lower portions of said substantially vertical bars, said grid being withdrawably disposed inside said chamber, each of said substantially vertical bars being of a depth many times its thickness and having substantially flat sides disposed transversely to said side walls and substantially flat narrow edges opposed to said side walls, the depth of said grid being such that said side walls rest upon and are supported by the narrow edges of said substantially vertical bars, a water inlet pipe disposed substantially horizontally inside said chamber near the top thereof and passing

through holes in said side members and said vertical bars, said water inlet pipe being perforated substantially along its whole length with two rows of small openings positioned between said vertical bars and so as to direct the cooling water supplied to said pipe on to the inner faces of said side plates to form a continuous fast moving de-

scending film thereon, and means for removing the descended cooling water from said cell at a rate sufficient to prevent enough accumulation of the cooling water to fill the cell.

DANIEL ALPHONSUS HACKETT.
